POLE REVERSING SWITCH

Arnold A. Bluemle and William Earl Brown, Anderson, Ind., assignors to General Motors Corporation, Detroit, Mich., a corporation of Delaware

Application August 13, 1941, Serial No. 406,698

8 Claims. (Cl. 200—6)

This invention relates to controlling mechanism for electric circuits and more particularly to controlling mechanism in which the direction of current flow through the make-and-break device of an ignition is periodically reversed.

An object of the present invention is to provide a switch for controlling an electrical circuit, such as an ignition circuit of an internal combustion engine, and so constructed that the direction of current will be changed by successive operation of the switch for reversing polarity of ignition circuit to obtain flat contact operation of the timer contacts.

Another object of the present invention is to provide a very simple and inexpensive form of pole reversing switch which may be easily mounted to suit the service for which it is intended.

Another object of the present invention is to provide a novel mounting for a pole reversing switch which may be readily incorporated with a switch adapted for use with starting apparatus including means for cranking an internal combustion engine.

Further objects and advantages of the present invention will be apparent from the following description, reference being had to the accompanying drawing wherein a preferred embodiment of the present invention is clearly shown.

In the drawing:

Fig. 1 is a plan view showing a fragment of the starting motor with a starting switch and pole reversing switch mounted thereon and showing the actuating means for the switches.

Fig. 2 is a side view of the switch and actuating means shown in Fig. 1.

Fig. 3 is an enlarged sectional view of the pole reversing switch taken on the line 3—3 of Fig. 2.

Fig. 4 is a plan view of the switch housing with the switch elements removed.

Fig. 5 is a rear plan view of the pole reversing switch and illustrating the same connected with the usual ignition system.

Fig. 6 is a plan view showing one side of the contact carrier used in the pole reversing switch.

Fig. 7 is a side view of the contact carrier.

Fig. 8 is a plan view showing the opposite side of the contact carrier shown in Fig. 6.

Fig. 9 is an end view of the ratchet collar used in the switch.

Referring to the drawing 20 designates a fragment of a frame of a starting motor. It will be understood by those skilled in the art that the frame 20 encloses an armature, pole pieces and field windings, not shown. The armature is mounted on a shaft which supports a gear or pul-

ley having a slidable splined connection with the shaft. The gear or pulley is adapted to be moved endwise into engagement with a gear or flywheel operated by the engine. Illustration of these parts is deemed unnecessary to understand the present invention. It is to be understood that the gear or pulley on the armature is moved endwise into engagement with the flywheel by a lever 21 suitably pivoted to the frame 20 of the starting motor. The lever 21 is connected with a rod 22, which extends through the floor board of the automobile to a pedal actuated by hand or foot, not shown. It is to be understood that when the pedal is depressed the rod 22 will move the lever 21 in counterclockwise direction as viewed in Fig. 2, to shift the gear or pulley endwise on the armature shaft into engagement with the flywheel of the engine to be started. This movement of the lever 21 will close a starting motor switch 23. The starting motor switch 23 includes a casing 24 attached to the frame 20 by screws 25 or in any other suitable manner. The casing 24 encloses a pair of stationary contacts and a movable contact. The movable contact is carried by a plunger 29 slidably supported by the casing 24. The plunger carries a cap 39. A spring 31 is interposed between the cap and housing to hold normally the movable contact separated from the stationary contacts.

A pole reversing switch 30 and the means for actuating said switch which comprises the present invention includes a cup-shaped housing 35, the open end of which is counterbored to provide an annular shoulder 36 and an annular flange 37. The flange 37 is provided with spaced tangs 38. The bottom wall 39 of the housing has an external apertured boss or hub 40 forming a bearing for a shaft 41. The internal face of the bottom wall 39 has a plurality of spaced teeth 42 concentrically arranged with respect to the aperture in the boss 40. These teeth are preferably integral with the bottom wall of the housing and extend away from the plane of said wall. An angular extension 43 supports the switch housing 35 on the motor frame 20. In the present instance the bracket 43 is shown as being integral with the housing, as shown in Fig. 3. It is to be understood that a separate bracket could be provided instead of the extension 43. In this case the bracket would be attached to the housing by spot welding or by other suitable means. The free end of the extension 43 is provided with apertures to receive screws 45 for attaching the extension to the motor frame 20. The shaft 41 rotatably supported in the bear-

ing aperture of the boss 40 has an enlarged end 46 to form a shoulder 47. This shoulder is adapted to bear against the internal face of the bottom wall 39. This enlarged portion 46 has flat sides 48. The other end of the shaft 41 is reduced as at 49 and said reduced portion is also provided with flat sides as shown in Fig. 2. The reduced end 49 of the shaft 41 projects through an aperture of a lever 50. The aperture in the lever corresponds to the contour of the reduced end so as to be driven by the lever. The reduced end 49 is riveted over against the lever to maintain the lever 50 and the shaft 41 in assembled relationship with the housing 35 as is apparent from the showing in Fig. 3.

An apertured contact carrier 55 of insulating material is rotatably mounted on the enlarged portion 46 of the shaft 41. One side of the contact carrier has a boss 56 and a plurality of equally spaced lugs 57, the face of the boss contacting a plane surface about the aperture in the bottom wall 39. The lugs 57 are arranged concentrically with respect to the boss and are located in the path of the teeth 42 on the bottom wall of the housing, said teeth cooperating with the lugs to prevent rotation of the carrier in a reverse direction. The other side of the contact carrier has the aperture counterbored at 58 with the bottom thereof defined by six equidistant serrations or teeth 59. This side of the contact carrier is also provided with three spaced pockets 60 about the counterbore for the reception of bridging contacts 62. Each pocket is provided with a depression 61 to form a seat for a compression spring 63. Each bridging contact may consist of a strip of flat metal the ends of which are bent at right angles to the main portion of the contact. Each compression spring bears against the bridging contact to urge yieldingly the bridging contact outwardly. Each bridging contact is provided with bosses or bulges 64 for engagement with stationary contact terminals.

The counterbore 58 of the contact carrier forms a bearing for a cylindrical ratchet collar 70. The ratchet collar 70 has a partition 70a within it, said partition dividing the collar into two compartments. One compartment of the collar is provided with a recess 73 complementary to the contour of the enlarged portion 46 so as to be driven thereby. This end of the collar has teeth 74 to form a ratchet connection with the teeth 59 in the bottom of the recess 58. The other compartment of the collar 70 receives a compression spring 74, the partition 70a forming a seat for one end of the spring 74 with the other end extending beyond the end of the collar.

A sub-assembly of conductor plates and stationary contact terminals for closing the open end of the housing 35 comprises a block 75 of insulating material having a recess 76 in axial alignment with the collar 70 to receive and form a bearing for the collar. The bottom of the recess 76 provides a seat for the other end of the spring 74. A plurality of headed rivets are carried by the block, the heads of which are preferably flush with the inner face of the block. The heads of the rivets form stationary contacts 81, 82, 83, 84 and 85. These contacts are arranged in a circular row. The shanks of the rivets project beyond the outer face of the block and extend through apertures provided in respective conducting plates and peened over as indicated in Fig. 3.

Referring to Fig. 5, the terminal contacts are electrically conducted to the conducting plates in the following manner, terminals 81 and 85 to

plate 90, terminal 82 to coil plate 92, terminal 83 to plate 93; and terminal 84 to ground plate 94 which is in turn connected to bracket 43.

Before the block 75 is assembled with the housing a gasket 95 is placed on the shoulder 36. The block rests on the gasket. The block is provided with suitable notches 96 to receive the tangs 38. The tangs are bent over against the rear side of the block to hold the block firmly against the shoulder 36 and prevent the block 75 from moving axially within the housing. When the block 75 is secured in position in the housing 35 the compression spring 74 is in a compressed state and constantly urges the collar 70 and the contact carrier toward the bottom wall of the housing and maintains the ratchet connection between the teeth on the collar and the teeth in the bottom of recess 58. The spring 63 in the pockets 60 urge their respective bridging contacts against the block 75.

The means for actuating the pole reversing switch is shown in Fig. 1 and Fig. 2. In this particular arrangement the lever 21 operates the lever 50 through a linkage 100 comprising a metal strap 101 having one end 102 pivotally mounted to the lever 21 by a stud 103. The strap is reduced at 104 to provide a shoulder 105. The reduced portion of the strap is provided near its end with an elongated slot 106 through which projects a stud 107 fixed to the lever 50. The stud also passes through a slot in one end of a clip 108. The other end of the clip is enlarged and is provided with spaced angular ears 109 which straddle the reduced portion 104 of the strap 101. The other end of the clip is provided with a slot and is held in assembled relationship with the stud 107 when the slot is fitted to an annular groove in the stud. A compression spring 111 is interposed between the ears 109 and the shoulder 105 and operates to urge the strap 101 to the right as viewed in Fig. 2.

The pole reversing switch is particularly used in an ignition circuit of an internal combustion engine, and is so mounted and connected, with respect to the starting motor shifting lever in the present instance, that each time the starting switch is closed the direction of flow of current through the make and break of the timer will be reversed.

Referring to Fig. 5 the pole reversing switch is shown connected in the ignition circuit shown diagrammatically. In this figure, 115 represents a storage battery or other source of current from which current will flow from one terminal of the battery through a lead 116 connected with an ignition switch 117. When the ignition switch 117 is closed the direction of flow will be as follows: from the ignition switch 117 the current will flow thru the primary winding of an ignition coil 118, lead 119, plate 92, terminal 82, a bridging contact 62, terminal 83, plate 93, lead 120, make-and-break device 121, lead 122, terminal 81, plate 90, terminal 85, another bridging contact 62, terminal 84, and ground plate 94.

The next time the operator desires to start the engine and the ignition switch is closed the rod 22 is depressed causing the lever 21 to move in a counterclockwise direction, as shown in Fig. 2 to close the starting switch 23. As the lever 21 is actuated the lever 50 is also actuated. The lever 50 is actuated through lever 101, spring 111, and clip 109. The lever 50 is rotated until it engages a stop lug 109. After the lever is stopped by lug 109, further travel of the lever 21 is permitted by the elongated slot 106 in link 101. The

purpose of the slot 106 is to take care of variations and wear of the stationary contacts in the starting switch 23. When the lever 50 is moved in a clockwise direction the shaft 41 is rotated in the same direction. This movement of the shaft 41 drives the collar 70 through the drive connection between the collar 70 and enlarged portion 46. The collar 70 drives the contact carrier 55 through the ratchet provision between the collar and carrier. This movement causes the contact carrier 55 to rotate substantially 60 degrees to change the positions of the bridging members 62 to connect a new series of terminals in the ignition circuit. The circuit completed will be from the battery 115, lead 116, switch 117, coil 118, lead 119, plate 92, terminal 82, a bridging member 62, terminal 81, plate 90, lead 122, make-and-break device 121, lead 120, plate 93; terminal 83, another bridging member 62, terminal 84 and ground plate 94.

It will be observed that in last referred to arrangements of the pole reversing switch contacts that the current flow through the make-and-break device is reversed to that set forth in the first instance. The current will flow in this direction until the pedal 21 is again actuated to close the starting switch 23.

When the operator releases manual pressure upon the pedal attached to the rod 22 a spring, not shown, will return the lever 21 to its normal position. As the pedal is returning to home position the strap 101 will move to the right causing the lever 50 and the shaft 41 to move in a counterclockwise direction, as viewed in Fig. 2, which actuates the collar 70 in the same direction. The collar is moved axially within the recesses 58 and 76 by the teeth 71 in the recess 58 to compress the spring 74 until a new set of teeth mesh. The contact carrier 55 is held stationary by reason of certain lugs 57 engaging the teeth 42 on the bottom wall 39 which prevents the contact carrier from moving in the reverse direction. With each succeeding operation of the pedal 21 to close the starting switch the contact carrier will be rotated substantially 60 degrees causing a reversal in the direction of flow of current through the make-and-break device from that which prevailed during the preceding connection. By this arrangement the pitting of the contacts of the make-and-break device will be greatly reduced and will remain in a better condition for a longer time than would be the case if the current flow is always in the same direction.

While the embodiment of the present invention as herein disclosed, constitutes a preferred form, it is to be understood that other forms might be adopted, all coming within the scope of the claims which follow.

What is claimed is as follows:

1. An electric switch comprising in combination; a housing; an oscillatable driving member supported by the housing; a closure for the housing; spaced stationary contacts carried by the closure; a collar rotatably supported by the closure and driven by the driving member; a carrier mounted for rotation upon the driving member and collar, said carrier supporting yieldable contacts for engagement with stationary contacts; a one-way driving connection between the collar and the carrier; and ratchet provision provided by the housing and the carrier operating to prevent reverse movement of the carrier upon movement of the driving member and collar in the non-operating direction.

2. An electric switch comprising in combination; a cup shaped housing; an oscillatable driving member supported in the bottom wall of the housing; means for actuating the driving member; a closure for closing the open end of the housing; stationary contacts carried by the closure; a recess provided by the closure; a collar rotatably supported in the recess and driven by the driving member; a carrier rotatably mounted on the driving member and the collar, said carrier supporting contacts for engagement with the stationary contacts; a one-way driving connection between the collar and the carrier; a spring disposed between the bottom of the recess and a partition provided by the collar for yieldingly urging the collar and carrier toward the bottom wall of the housing; and cooperating provisions provided by the housing and the carrier and operating to prevent reverse movement of the carrier upon movement of the driving member and the collar in the non-operating direction.

3. An electric control device comprising in combination; a pair of spaced walls; an operating shaft journalled in one of the walls; a driven shaft adapted to be slidably and rotatively journalled in the other wall; a splined connection between the shafts whereby the operating shaft drives the driven shaft; a carrier journalled on the driven shaft, said carrier carrying yieldable contacts for engagement with stationary contacts supported by the other wall; a spring for continuously biasing the driven shaft in one direction to maintain the splined connection; ratchet provisions between the inner end of the driven shaft and the carrier whereby the carrier is rotated in one direction only upon actuation of the operating shaft in one direction; ratchet provision between the carrier and the first mentioned wall preventing reverse rotation of the carrier when the actuating shaft is moved in the opposite direction of rotation.

4. An electric switch comprising in combination; spaced stationary contacts; a drive shaft; a driven shaft slidably and rotatively supported in alignment with the driven shaft; a spline connection between the shafts; a spring for continuously urging the driven shaft axially in a direction for maintaining the spline connection between the shafts; a rotor journalled upon one of the shafts, said rotor supporting yieldable contacts for engagement with the stationary contacts; ratchet provisions between driven shaft and the rotor whereby the rotor is rotated by the driven shaft in one direction only; ratchet provision between the rotor and a stationary part to prevent reverse rotation of the rotor; and means for actuating the drive shaft in either direction of rotation.

5. An electric switch comprising in combination; a housing having opposed walls; an oscillatable driving member supported by one of the walls; a collar rotatably supported by the other wall and driven by the driving member; a carrier mounted for rotation by the collar, said carrier supporting biased contacts for engagement with stationary contacts supported by the housing, a one-way driving connection between the collar and carrier; and ratchet provisions provided by the housing and the carrier preventing reverse movement of the carrier upon movement of the driving member and collar in the non-operating direction.

6. An electric switch comprising in combination; a housing having opposed walls; a driving

member supported by one of the walls; a sleeve rotatably supported by the other wall and driven by the driving member; a carrier mounted for rotation by the driving member through the sleeve, said carrier supporting yieldable contacts for engagement with stationary contacts supported by the housing; a one-way driving connection between the sleeve and carrier; ratchet provisions provided by the housing and the carrier preventing reverse movement of the carrier upon reverse rotation of the driving member.

7. An electric switch comprising in combination; spaced stationary contacts; a sleeve mounted for axial and angular movement relative to the stationary contacts; a non-conducting member journaled upon the sleeve and carrying biased contacts for engagement with the stationary contacts; driving connections between the collar and non-conducting member; ratchet provisions provided by a stationary part and the non-conducting member whereby the non-conducting member can move in one direction of rotation only; operating means for actuating the collar in either direction of rotation; and spring means cooperating with the sleeve to exert an axial directed force thereon normally to maintain said mentioned driving connections and the ratchet provisions effective.

8. An electric switch comprising in combination; a pair of shafts supported in axial alignment one of which is capable of moving axially relative to the other; a spline connection between the shafts whereby the shafts rotate together in either direction of rotation; a non-conducting carrier rotatably and axially supported by one of the shafts said carrier supporting yieldable contacts for engagement with stationary contacts; ratchet provisions between the shaft capable of axial movement and the carrier whereby the carrier is rotated in one direction of rotation; ratchet provisions between the carrier and a stationary part for preventing reverse rotation of the carrier when the shafts move in the reverse direction of rotation; and resilient means held under compression acting on said axially movable shaft for maintaining the ratchet provision effective.
